UNITED STATES PATENT OFFICE

93,147

DESIGN FOR A BOTTLE

Helena J. Titus, New York, N. Y.

Application June 9, 1934, Serial No. 52,115

Term of patent 14 years

To all whom it may concern:

Be it known that I, HELENA J. TITUS, a citizen of the United States of America, and residing in the State, county, and city of New York, have invented a new, original, and ornamental Design for a Bottle, of which the following is a specification, reference being had to the accompanying drawing, forming part thereof.

Figure 1 is a side elevational view of a bottle showing my new design; and Figure 2 is a substantially transverse sectional view taken on lines 2—2 of Figure 1.

I claim:

The ornamental design for a bottle, as shown.

HELENA J. TITUS.
